UNITED STATES PATENT OFFICE.

JAMES PICKLES, OF BRADFORD, ENGLAND.

SAND-MOLDING MACHINE.

No. 841,569.

Specification of Letters Patent.

Patented Jan. 15, 1907.

Application filed October 18, 1905. Serial No. 283,228.

To all whom it may concern:

Be it known that I, JAMES PICKLES, a subject of the King of Great Britain, and a resident of 11 Moor View Terrace, Killinghall 5 Road, Bradford, in the county of York, England, have invented certain new and useful Improvements in Sand-Molding Machines, of which the following description, together with the accompanying sheets of drawings, is a specification.

This invention has reference to a sand-molding machine of a class which enables the user or operative to manually ram the sand within the boxes or to employ pressure-exerting devices provided on the machine for carrying out such ramming actions; and said invention consists in mounting and arranging in combination the table which carries the pattern-plate to form the mold, the pressure-exerting devices, and a table for receiving the sand-mold when produced in such manner that the employment of these several parts by the operative is greatly facilitated, and the liability of the sand-mold being damaged by the falling into or upon it of any loose sand or other matter after it has been formed is entirely obviated.

In carrying my invention into effect I make use of the devices hereinafter described 30 and as illustrated by the accompanying sheets of drawings, in which—

Figures 1 and 2 are front and end elevations, respectively, of a machine constructed and arranged in accordance with my invention. 35 Fig. 3 is a sectional end elevation of certain parts of the machine and shows the pressure-exerting devices in position, as when ramming the sand to form the sand-mold. Fig. 4 is a similar view to Fig. 3, but shows the table 40 upon which the mold is supported when being formed and the table which receives the mold when finished, as hereinafter explained. The pressure-exerting mechanism is omitted from Fig. 4.

The end frames A A', standards B B', and the cross-stay C, with its projecting arm D, form the fixed framework of the machine.

The pressure-exerting device or rammer consists of the ramming-plate a, mounted 50 upon the screwed adjusting-arms b b', having their lower extremities b' b' fixed upon the cross-shaft c, which is acted upon by the counterbalancing-weight d, mounted upon the lever d', pivotally carried by the swinging link d', so that its vertical movements in the slots A² of the end frame A A' may be thereby

rendered more easy to carry out by the operative, as hereinafter explained.

The arms b' b' are arranged to be operated by the handle e, which is fixed upon the shaft f, extending from one end frame A to the other A'. On or near the extremities of this shaft f are secured the arms g g', which are coupled by the links h h' to the arms b b', so that the movements of the handle e may be 65 by these several parts transmitted to the rammer a. These parts assume their normal positions (shown by Figs. 1 and 2) when the upper surface of the molding-box k or table k' is desired to be clear or open to allow the 70 filling of the box k with sand or for other purposes.

The table k', which carries the pattern s, which is fitted to it in the well-known manner, is mounted by its pivotal shafts k² k³, 75 taking into bearings or standards B B', and on or in connection with this table k', I provide the usual means for detachably securing the molding-box k upon it, so that as said table is revolved upon its shafts k² k³ the box 80 k may be carried with it until released therefrom by its securing means, as is well understood.

Beneath the table k', I mount another table m, which is supported by the screwed adjusting-bolts m' m' m', secured to the cross-pieces n n, which are formed to slide upon, so as to be guided by the projecting arm D; secured to or forming part of the cross-stay C. The arm D takes the form of a guide, on which 85 is mounted a sliding frame 10, to which the cross-pieces n n are connected to form a structure movable as a unit. The cross-pieces n n are operated by the links p p, pivotally connected to the sliding frame 10, and 90 to the arms q q, fixed upon the shaft r, which is mounted to oscillate in bearings on the end frames A A'. This shaft r has the handle-lever r' and counterbalancing weighted lever r² fixed upon it in order that the user may 95 operate it, as hereinafter described.

Assuming that an empty box k has been placed over the pattern-plate s while the several parts are in their normal positions, (shown by Figs. 1 and 2,) the molding-sand is then 105 placed in said box in the usual manner, on which the user moves the handle e to bring the rammer a over and down upon the box k' to ram said sand, as desired, at which time or by which movement the parts operated by 110 the handle e will have been brought into the positions shown by Fig. 3. On these pressing

or ramming actions being completed the handle *e* is released, and the parts it operates return to the position shown by Figs. 1 and 2. The table *k'* and its box *k* are then turned over or oscillated upon the pivotal bearings *k²* *k³*, so that the box *k* and its sand-mold therein are brought beneath the table *k'*, as shown by Fig. 4. The operator then raises the table *m* by moving the handle *r'* until said table presses against the box *k*, also as shown by Fig. 4, on which said box *k* is relieved of its attachment to the table *k'* and so will rest upon the table *m*, which on being lowered through the handle *r'*, being again operated, will bring with it the box *k* and the sand-mold within it more accurately and with greater precision than it is possible for the operative to raise said sand-mold and box from off the pattern *s* should the table *k'* be fixed as heretofore, while by the table *k'* thus being turned over during the withdrawal of the mold from the pattern it acts as a shield or protector for said mold, as hereinbefore described.

By this construction it will be seen that the guides for the rammer are formed in the end standards, while the guide for the table *m* is located intermediate of the end standards. There is therefore no liability of an interference between the two structures in

operation, nor is there a requirement of an enlarged frame, such as would be required were both guides located in the end standard.

Such being the nature and object of my invention, what I claim is—

A sand - molding machine comprising a supporting-frame formed of end standards and a cross-stay; a guide carried by said cross-stay and extending downwardly therefrom intermediate the end standards; a sliding frame carried by said guide, said sliding frame carrying a table; a revoluble table supported above said sliding table; a rammer movable from and to a position above said revoluble table, said rammer having its pivot end mounted within slots formed in said end standards, whereby a vertical limited movement may be imparted to said rammer; means for moving said rammer to its position above the revoluble table and then vertically in a downward direction; and means for moving said sliding table vertically to a point in juxtaposition to said revoluble table.

In testimony whereof I have affixed my signature in presence of two witnesses.

JAMES PICKLES.
